George Wessell

UNITED STATES PATENT OFFICE.

GEORGE WESSELL, OF BROOKLYN, NEW YORK.

DISH-PAN SUPPORT.

1,180,353.

Specification of Letters Patent. Patented Apr. 25, 1916.

Application filed April 24, 1915. Serial No. 23,730.

To all whom it may concern:

Be it known that I, GEORGE WESSELL, a citizen of the United States, and residing at Brooklyn, in the county of Kings and 5 State of New York, have invented certain new and useful Improvements in Dish-Pan Supports, of which the following is a specification, such as will enable those skilled in the art to which it appertains to make and 10 use the same.

This invention relates to dish-pan supports, and the object thereof is to provide an improved device of this class for use in water sinks, tubs or similar receptacles, and 15 which is strong and durable in construction and convenient in use or operation, and which may be folded up and suspended from a hook or other support when not in use.

20 The invention is fully disclosed in the following specification, of which the accompanying drawing forms a part, in which the separate parts of my improvement are designated by suitable reference characters 25 in each of the views, and in which:—

Figure 1 is a plan view of an ordinary water sink with my improved dish-pan support therein and indicating a dish-pan in dotted lines; Fig. 2 a section on the line 2—2 30 of Fig. 1; Fig. 3 a view of the support removed from the sink and with part of the construction broken away; and, Fig. 4 a view showing the support folded up or collapsed.

35 In the drawing forming part of this specification, I have shown at *a* an ordinary water sink, which, as usual, is approximately rectangular and oblong in form and at the back of which is a back board *a*², but the 40 sink *a* may be of any desired form or shape and in Fig. 2 I have shown a dish-pan *b* mounted on my improved support *c*.

The support *c* is composed of two separate strips of sheet metal as shown at *c*¹ and 45 *c*² which are pivotally connected centrally thereof by a pivot *d*, and the strips *c*¹ and *c*² are provided with downwardly directed legs *c*³, the lower ends of which are provided with braces *c*⁴ which extend inwardly 50 and radially and are provided with over-

lapping feet members *c*⁵ through which the rivet or pivot pin *d* passes. The rivet or pivot pin *d* is provided at its lower end with a head *d*² and its upper end is riveted and countersunk in the top strip *c*¹. 55

The support *c* may be composed, and is preferably composed of steel strips, and the construction shown and described, makes a strong and substantial frame which may be collapsed or partially collapsed, or folded 60 together, as shown in Fig. 4, so that said support may be hung up or suspended from a hook or nail when not in use.

In the construction shown the support *c* is of less vertical dimensions than the depth 65 of the sink *a* and the dish-pan *b* when placed thereon is securely supported, and when the support is placed in one end portion of the sink the lateral movement of the pan to any considerable extent is prevented as well as 70 its movement longitudinally in one direction by the walls of the sink, but my invention is not limited to the height of the support and any suitable vertical dimensions may be given thereto. 75

The support when made of steel may be nickel-plated so as to prevent its rusting, or being otherwise injuriously effected by water, and it will be understood that the 80 said support may be placed in any desired position, or in any part of the sink.

Having fully described my invention, what I claim as new and desire to secure by Letters Patent, is:—

A dish-pan support composed of two 85 metal strips which are pivoted together centrally and the ends of which have downwardly directed legs provided at their lower ends with upwardly and inwardly directed brace members having overlapping parts 90 through which the pivot pin which connects said strips passes.

In testimony that I claim the foregoing as my invention I have signed my name in presence of the subscribing witnesses this 95 22nd day of April, 1915.

GEORGE WESSELL.
